(57) **CLAIM**

We claim the ornamental design for an information handling system, as shown and described.

DESCRIPTION

FIG. 1 is a front perspective view of the information handling system comprising the present invention; FIG. 2 is a front elevation view thereof; FIG. 3 is a rear elevation view thereof; FIG. 4 is a right side view thereof; FIG. 5 is a left side view thereof; FIG. 6 is a top view thereof; FIG. 7 is a bottom view thereof; FIG. 8 is a bottom rear perspective view thereof; FIG. 9 is a front perspective view thereof in an open position; FIG. 10 is a front perspective detail view as indicated by FIG. 1; and, FIG. 11 is a top detail view as indicated by FIG. 6. Broken lines shown in the drawings showing portions of the information handling system, form no part of the claimed design; the broken lines indicating areas of the figures shown enlarged form no part of the claimed design.

1 Claim, 8 Drawing Sheets
